UNITED STATES PATENT OFFICE.

WILLIAM MAEVERS, OF NEW YORK, N. Y.

DESIGN FOR LAMP-SHADES.

Specification forming part of Design No. 6,897, dated September 30, 1873; application filed June 14, 1873.
[Term of Patent 14 years.]

To all whom it may concern:

Be it known that I, WILLIAM MAEVERS, a resident of New York city, and subject of the Empire of Germany, have invented and produced a new and original Design for a Lamp-Shade, which I denominate the "Mammoth Rose Light Shade," and of which the following is a specification:

The design is fully represented in the accompanying drawings. It consists of an artificial rose, *a*, of any desired color, varying from five to eight inches or more in diameter, supported, with its face in a vertical position, by a stem, *b*, attached to the rear side of the said rose, the stem *b* having a foot or base, *c*, which supports the whole device in a vertical position.

This rose may be surrounded by a border of other artificial flowers and leaves, as at *d*.

What I claim as my invention is—

1. A lamp-shade, consisting of an artificial rose, *a*, attached to a vertical stem, *b*, with a base, *c*, presenting an appearance substantially as in the drawings.

2. A lamp-shade, consisting of an artificial rose, *a*, having a border of artificial flowers and leaves, a vertical stem, *b*, and a base, *c*, presenting an appearance substantially as in the drawings.

WILLIAM MAEVERS.
